FLASHLIGHT DEVICE

Gwilym F. Prideaux, South Euclid, Ohio, assignor
to General Electric Company, a corporation of
New York

Application July 29, 1932, Serial No. 625,988

1. Claim. (Cl. 240—10.61)

My invention relates to illuminating devices and particularly to portable battery or flashlight lamps. The principal object of my invention is to provide such a lamp which will be of simple and inexpensive construction. Battery lamps as made at the present time comprise a dry battery or cell, a light source and a casing. According to my invention, the casing is dispensed with and further, the battery and the light source, such as an incandescent lamp, are constructed as a single, permanent unit which may be discarded in its entirety when the battery becomes exhausted.

Other features and advantages of my invention will appear from the following description of species thereof and from the drawing.

In the drawing Fig. 1 is a perspective view of a flashlight lamp comprising my invention; Fig. 2 is a partly sectioned elevation thereof; Fig. 3 is a partly sectioned elevation of a modification; and Fig. 4 is a partly sectioned elevation of another modification.

As shown in Figs. 1 and 2, the dry battery comprises a container 10 within which are disposed the other battery elements (not shown). Said container 10, which is generally made of zinc and serves as one of the electrodes, has a portion 11 which extends beyond the surface 12 of the pitch or other seal of the battery. The incandescent lamp portion of the device preferably comprises a bulb having a thickened or lens portion 13, such as disclosed in United States patent application Serial No. 584,063, Pipkin. Said lens portion 13 preferably consists of a spherical ball of glass and has a downwardly depending neck portion 14 fused thereto. A filament 15, sealed in said neck portion 14, is mounted on inner lead wires 16—17 which pass through and are sealed in said neck portion and terminate in outer lead wires 18—19. The outer lead wire 19 is connected to the center terminal 20 of the battery and the lead wire 18 passes through a short length of tubing 21, preferably of rubber, which extends through a hole 22 in the extended portion 11 of the container 10 and projects a short distance therebeyond. Sealing cement 23 is poured into the portion 11, the lamp is pushed down to insert the lower portion of the neck 14 therein, and the top of said extended portion 11 is crimped as at 24 to just cover the largest diameter of the spherical lens 13. A button 25 is connected to the end of the lead wire 18. The section of rubber tubing 21 which projects beyond the container serves as a spring to hold the circuit open. When the button 25 is depressed it

contacts with said container 10—11, thus closing the circuit and lighting the filament 15. The inside of the rubber tubing 21 is preferably made sufficiently larger in diameter than the lead-in wire 18 to allow for the small movement necessary when depressing the button 25 to close the circuit. The unit may be made quite attractive by coloring the container 10 or otherwise applying various designs thereon.

It may be desirable to combine the seal of the battery with the cementing-in of the lamp as shown in Fig. 3 wherein the sealing cement 23 in which the lamp 13—14 is set serves simultaneously as the battery seal. Said sealing cement 23 is poured in the container 10 onto a disc 25' which may be of cardboard. Said disc 25' rests on a bibulous sack 26 which contains the battery mix 27 and is saturated with a chemical such as sal ammoniac or zinc chloride which comprises the electrolyte. A carbon electrode 28 is disposed in the battery mix 27 and has a metal cap 29 on the end thereof to which the lead wire 19 may be attached.

The modified species shown in Fig. 4 comprises a standard miniature cell 30 together with a lamp 13—14 having the lead wire 18 fastened to the center terminal 31 of said cell 30 and mounted in sealing cement 32. A translucent cap 33 having a hole 34 therein is placed over the lamp 13—14 and extends over the upper part of the cell 30. The hole 34 is of a slightly smaller diameter than the spherical lens 13 thereby preventing the cap 33 from slipping past said lens. Said cap 33 may be affixed to the cell 30 by means of a cement. The switching arrangement is different than that in Fig. 2 and comprises a button 35 having two prongs 36—37 attached thereto and projecting into the cap 33 through a hole 38. The prong 37 is bent down and fastened to the container of the cell 30 while the prong 36 extends horizontally to within a short distance of the neck 14 of the lamp. A ball of solder 39 is fixed to the outwardly projecting portion of the lead wire 17 adjacent to the neck 14. When the button 35 is depressed a hooked portion 40 on the end of the prong 36 contacts with the ball of solder 39 to close the circuit and light the filament 15. The translucent cap 33 consists preferably of celluloid or of a synthetic resin such as the urea or thiourea compounds. Examples of such resins are those commercially known as Beetle and Elaskon. Cellulose compounds may also be used such as the acetate, nitrate or benzoate. The sealing cement 32 may also comprise the battery seal as in Fig. 3.

What I claim as new and desire to secure by Letters Patent of the United States, is:

A flashlight comprising a lamp having a bulb with an electric light source therein, leading-in conductors sealed in said bulb and extending exteriorly thereof, a container comprising one electrode of an electric battery having also a second electrode, said lamp being fixedly mounted in said container and having one of the leading-in wires thereof attached to said second electrode, an elastic insulating tube extending outwardly

through an opening in the wall of said container, the second leading-in wire of said lamp extending outwardly through said elastic tube, and a metal cap disposed at the outward end of said tube and connected to said second leading-in wire, said elastic tube normally holding said cap away from said container but allowing said cap to be pressed against said container to close the circuit through said lamp.
